US00D971371S

(12) **United States Design Patent** (10) Patent No.: **US D971,371 S**
(45) Date of Patent: **** Nov. 29, 2022**

(54) **RIFLE SCOPE**

(71) Applicant: **UAB "Yukon Advanced Optics Worldwide", Vilnius (LT)**

(72) Inventor: **Siarhei Gurynovich, Vilnius (LT)**

(**) Term: **15 Years**

(21) Appl. No.: **35/512,418**

(22) Filed: **Feb. 26, 2021**

(80) **Hague Agreement Data**

Int. Filing Date: **Feb. 26, 2021**

Int. Reg. No.: **DM/214902**

Int. Reg. Date: **Feb. 26, 2021**

Int. Reg. Pub. Date: **Aug. 27, 2021**

(51) LOC (13) Cl. **22-01**

(52) U.S. Cl.

USPC **D22/109**

(58) **Field of Classification Search**
